UNITED STATES PATENT OFFICE

2,078,803

ELECTRIC CIRCUIT BREAKER

Otto Mayr, Berlin-Karlshorst, Germany, assignor
to General Electric Company, a corporation of
New York

Application June 16, 1936, Serial No. 35,568
In Germany July 15, 1935

5 Claims. (Cl. 200—148)

My invention relates to electric circuit breakers, more particularly to the contact structure thereof, and has for its principal object the provision of an improved circuit breaker of the type wherein the contacts engage in plug and socket relation.

In circuit breakers of the aforesaid type, the socket or fixed contact is generally formed of segments circumferentially located about the movable rod contact and biased into engagement therewith by springs, either individually, or as a group by a surrounding garter-type spring. In these arrangements the electrical connections and the mechanical mountings between the segments and the corresponding breaker terminals may be complicated and expensive, both in construction and maintenance.

In accordance with my invention, these disadvantages are overcome by providing resilient positioning means for each pair of a plurality of segments forming a ring shaped contact, said means positioning said segments with respect to and biasing them into contact engagement with both the coacting movable rod contact and the stationary conducting structure associated with the corresponding breaker terminal.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view, partly in section, of a circuit breaker of the gas-blast type embodying the present invention; Fig. 2 is a sectional view taken along the line 2—2 of Fig. 1; Fig. 3 is a view similar to Fig. 2 illustrating a modified form of the contact structure, and Fig. 4 is another similar view showing a more simplified form.

In Fig. 1 there is shown, by way of example, a circuit breaker of the gas-blast type comprising a cylindrical insulating casing 1 in which are mounted the relatively fixed contact structure 2 and the movable contact structure 3, comprising in the present instance a rod contact. The breaker is shown in the open circuit position, and in the closed circuit position the rod 3 is elevated by suitable operating means (not shown) so as to engage the fixed contact structure 2.

The fixed contact structure 2, referring also to Fig. 2, comprises a plurality of pairs of coacting segments 4 adapted to surround and engage the rod contact 3 in the closed circuit position. Each pair of segments 4 is interconnected by resilient supporting and positioning means comprising a

through-bolt 5 and a pair of springs 6. For convenience in assembly and maintenance, the heads of the through-bolts 5 are elongated, as contrasted with the conventional circular shape, and coact with cup-shaped members 7 which provide seats for the springs 6 bearing against the segments 4. The cup members 7 are provided with elongated slots corresponding to the size of the bolt heads so that during assembly the bolt heads are merely inserted through the slots and turned 90 degrees, thereby holding the springs in compressed position with respect to the through bolt and segments 4.

In addition to maintaining the segments in contact engagement with the rod 3, the springs 6 also bias the lateral clamp-shaped extensions 4' of the segments into contact engagement with a conducting contact carrier or support 8. The support 8 in the present instance comprises a loop-shape rod structure, the lower free arms of which are engaged by the segments 4 and the upper part suitably connected to the breaker terminal stud 9.

From the foregoing, it will be clear that the electrical connection between the breaker terminal 9 and the segments 4 constituting the main fixed contact structure is considerably simplified in that a number of bolted and flexible connections, previously used, are avoided. Furthermore, segments 4 which necessarily have a limited amount of movement because of occasional contact misalignment are not only in good electrical engagement with the support 8 but also are mechanically clamped thereto by the radially disposed extensions 4' for holding the segments in proper position.

The electrical connection between the other terminal and the rod contact 3 may be made in a similar manner. Here the contact segments 4 are in sliding engagement at all times with the rod 3 and are electrically and mechanically connected to the loop-shaped conducting support 8 in the manner above described. The support 8, which is fixed as in the previous instance, is connected to the other breaker terminal 10 by means of a braided conductor 11 which is connected to a conducting end cap 12 forming part of the terminal structure. The rod 3 is guided through the lower end of the support 8 at 8' and the cap 12 for vertical reciprocal movement.

The gas blast feature of the breaker, which is shown merely by way of example, comprises a pipe 13 communicating with a suitable source of fluid pressure (not shown) leading into the lower end of the casing 1 through the cap 12. The fixed contact structure 2 is preferably mounted in a

suitable baffle structure 14 forming with the segments 4 a nozzle-shaped passage 15 through which gas may exhaust from the lower part of the casing to the upper part beyond the baffle. Circuit interruption is effected by lowering the rod 3 to the open position coincident with the admission of high pressure gas through the pipe 13. The arc between the contacts 2 and 3 is interrupted by the gas blast through the passage 15.

10 A muffler device is provided at the upper part of the casing 1 beyond the exhaust from the passage 15 comprising a pair of spaced perforated plates 16 forming a space containing a plurality of small rings 17. The muffling device is positioned above the contact carrier 8 on the terminal stud 9. A cup-shaped gas deflecting member 18 is likewise secured to the stud 9 above the muffler and is positioned by a stud bushing 19 between the lower side thereof and the carrier 8, and a nut 20 threaded on the bolt 8. With this arrangement, the high velocity gas exhaust from the passage 15 on circuit interruption is silenced to a great extent by the muffling device at 16-17, the exhaust gases finally issuing from the top of the 25 casing 1 around the outer periphery thereof.

The assembly of the above described structure within the casing 1 may be accomplished in any suitable manner. I have shown the fixed and movable contact structures secured within the 30 insulating casing to a pair of metal sleeves 21 and 22, respectively, at the upper and lower ends of the casing 1. The baffle structure 14 and the muffling device are suitably secured to the inner wall of the sleeve 21, as indicated, as are the contact 35 retaining spider 23 and the contact carrier supporting strut 24 to the lower sleeve 22.

Where a contact structure of higher current carrying capacity is required, the arrangement shown by Fig. 3 may be used wherein four pairs 40 of contact segments are circumferentially disposed about the rod contact 3. In this arrangement, as in the previous case, each pair of contact segments is provided with resilient positioning means comprising a through-bolt and biasing 45 springs 5 and 6, respectively, and is resiliently clamped to a depending member of the contact carrier 8. There is in this case four such members depending from the terminal stud 9 and spaced 90 degrees apart.

50 Fig. 4 illustrates a simplified form of contact structure wherein a single pair of contact segments 4 makes contact between the movable rod 3 and the stationary contact support 8, the biasing and supporting means for the segments being 55 the same as above described.

It should be understood that my invention is not limited to specific details of construction and arrangement thereof herein illustrated, and that changes and modifications may occur to one 60 skilled in the art without departing from the spirit of my invention.

What I claim as new and desire to secure by Letters Patent of the United States, is:—

1. An electric circuit breaker comprising co-acting fixed contact structure and a movable rod contact, said fixed contact structure including a terminal, a plurality of conducting members connected to and extending from said terminal, a pair of contact segments for engaging each conducting member so as to clamp said member, said pairs of segments surrounding the movable rod contact in the closed circuit position, and resilient positioning means for each pair of said

segments for biasing the same into contact engagement with both the corresponding conducting member and movable rod contact.

2. An electric circuit breaker comprising a fixed socket contact structure and a coacting movable rod contact arranged to be in sliding contact engagement therewith, said fixed contact structure including a plurality of pairs of contact segments arranged circumferentially about said rod contact, said segments having extensions radially disposed with respect to said rod contact, conducting means engaged in clamping relation by the extensions of each pair of segments, and resilient positioning means for biasing each pair of segments into contact engagement with said rod contact and conducting means respectively. 1)

3. An electric circuit breaker comprising coacting fixed contact structure and a movable rod contact, said fixed structure including a terminal member, a loop-shaped contact carrier connected to said terminal member, a pair of contact segments engaging in clamping relation each arm of said loop-shaped members, said contact segments arranged circumferentially about said rod contact in closed circuit position and adapted to 20 be in relative sliding engagement therewith, and resilient means for biasing each pair of contact segments into contact engagement with said rod and into clamping engagement with said contact carrier arm. 25

4. An electric circuit breaker comprising a fixed contact structure and a coacting movable rod contact, said fixed contact structure including a terminal, conducting means connected to said terminal, a plurality of contact segments arranged circumferentially about said movable rod contact in the closed circuit position, each pair of said contact segments provided with means for resiliently biasing the same into contact engagement with both said contact rod and conducting means, said segments likewise being in clamping engagement with said conducting means, and fixed terminal structure coacting with said movable rod contact including a second terminal, conducting means electrically connected to said 35 terminal, and a plurality of pairs of contact segments resiliently biased and similarly arranged to engage both said rod contact and conducting means respectively, said last-named segments being in sliding contact engagement with said rod 40 in both the open and closed circuit positions of said circuit breaker. 45

5. An electric circuit breaker of the gas-blast type comprising a casing, relatively movable contacts co-acting within said casing and means for admitting gas under pressure to one end of said casing for exhausting at the other end of said casing, said fixed contact structure including a baffle disposed transversely of said casing provided with a central passage, a plurality of contact segments disposed circumferentially about and extending radially with respect to said passage so as to form with said passage a nozzle-like exhaust opening through said baffle, a terminal disposed at the exhaust end of said casing, a contact carrier connected to said terminal and extending to said baffle, and resilient positioning means for biasing each pair of segments into contact engagement with said movable rod contact in the closed circuit position and into clamping engagement with said conducting means. 60
